SILO ROOF

Charles A. Bangert, Columbus, Ohio, assignor to
 Lamneck Products, Incorporated, Columbus,
 Ohio, a corporation of Ohio

Application April 22, 1936, Serial No. 75,838

2 Claims. (Cl. 108—32)

My invention relates to silo roofs. It has to do, more particularly, with a silo roof which is of sheet metal construction and is adapted to be applied to various types of silos.

5 Silo roofs have been constructed in the past from sheet metal. These silo roofs are usually made of a number of sheets or panels of sheet metal which have their adjacent edges connected together. These sheets or panels are so arranged 10 as to form a substantially frusto-conical structure which is adapted to be mounted on the upper end of a substantially circular silo. The sheets or panels are usually so joined together at their edges that slight relative movement between the adjacent panels is permitted in order 15 to make possible the application of the roof to a silo which is out of round or of an odd diameter. However, the joint between adjacent sheets or panels which has been provided in the past 20 for permitting slight relative movement therebetween has a number of undesirable features. In the first place, the movement which is permitted is not sufficient. Furthermore, the joint has been so constructed that a number of angular 25 bends in the edges of the adjacent sheets are necessary to form the complete joint. This makes it difficult to form the joint. Also, complicated and expensive securing clips have been necessary 30 for securing the edges of the adjacent panels together.

Another disadvantage of prior art silo roofs of the type indicated resides in the type of filling door which has been provided in the side of the roof. This door is usually of the hinged type 35 which swings outwardly. This type of door is very dangerous because if opened during a high wind there is danger of its being swung outwardly by the wind with such force as to knock the workman who opens it off the silo.

40 One of the objects of my invention is to provide a self-supporting silo roof structure which is made up of a plurality of panels joined together which are so formed as to reinforce themselves.

45 Another object of my invention is to provide a silo roof structure made up of a plurality of panels which are so joined together as to permit considerable relative movement between adjacent panels, the joint between adjacent panels 50 being of a simple structure, and easy to form and assemble, and the securing means required at the joint being simple and easy to apply.

Another object of my invention is to provide a door in the roof structure which is of simple 55 structure and is safe to operate.

The preferred embodiment of my invention is illustrated in the accompanying drawing wherein in similar characters of reference designate corresponding parts and wherein:

Figure 1 is a perspective view of a complete 5 silo roof structure made in accordance with my invention.

Figure 2 is a perspective view of a portion of 10 the roof structure showing the door structure applied thereto.

Figure 3 is a perspective view, partly broken 15 away, illustrating the joint between two adjacent panels.

Figure 4 is a front elevational view, partly cut 20 away, of the door structure illustrated in Figure 2.

Figure 5 is a section taken substantially along line 5—5 of Figure 4.

Figure 6 is a detail illustrating the bracket 25 which I preferably employ in securing the roof structure to the silo.

With reference to the drawing and particularly to Figure 1, I have illustrated a silo roof structure of the gambrel type embodying a lower portion 1 of frusto-conical form and an upper 25 portion 2 also of frusto-conical form but inclined to a greater extent than the portion 1.

Each of the portions 1 and 2 is made up of a plurality of self-supporting panels 3 each of which is formed of a single sheet of sheet metal. 30 As indicated in Figure 1, each of the panels gradually decreases in width from its lower to its upper edge. Midway between the side edges of each panel a reinforcing rib 4 is formed which extends from the lower edge to the upper edge 35 of the panel. This rib 4 is of arcuate cross-section and, therefore, is easy to form in the panel. Furthermore, it gradually decreases in width from its lower end to its upper end in accordance with the decrease in width of the panel. 40

In Figure 3 I illustrate the joint which I provide for securing the adjacent panels together in such a manner as to permit slight relative movement therebetween. As illustrated in this figure, one of the adjacent panels has its edge bent to 45 form a rib 5 of substantially arcuate cross-section. This rib 5 gradually decreases in width from the lower end of the panel to the upper end thereof as illustrated in Figures 2 and 3. The other adjacent panel 3 has its adjacent edge bent 50 to form a similar rib 5a which is of arcuate cross-section and gradually decreases in width from the lower end of the panel to the upper end thereof. This rib 5a is of less radius than the rib 5. The rib 5a is adapted to fit within the 55

rib 5. Since both of these ribs are of arcuate cross-section, they may be formed in the sheet very easily. A plurality of bolts 6 pass through the rib 5 and through transverse slots 1 formed in the rib 5a. Thus, it will be apparent that this joint will permit considerable relative movement between the two adjacent panels. These joints are illustrated generally by the numeral 8 in Figure 1. Because the adjacent panels are joined together by this type of joint, the roof structure may be readily applied to silos which are out of round. This is important because it often happens that the silo walls are not exactly circular.

15 The filling door which I preferably provide in
the side of the portion 1 of the roof structure
is illustrated best in Figures 2 and 4. As illus-
trated, an opening 9 is provided in the bottom
portion of one of the panels 3. This opening is
20 adapted to be covered or exposed by means of
a sliding door 10. The door 10 embodies a single
sheet of material which has a rib 11 of arcuate
cross-section formed midway between the side
edges thereof and extending for the entire height
25 thereof. This rib serves to reinforce the door.
The side edges of the door are curled inwardly as
indicated at 12 in Figure 5. These curled por-
tions 12 fit around vertically disposed rods 13.
As indicated, the lower ends of the rods 13 are
30 loosely mounted for lateral movement in bracket
members 14. These rods 13 are disposed directly
adjacent the edges of the opening 9. They ex-
tend upwardly a distance equal to substantially
twice the height of the door 10.

35 Above the opening 9 a member 15 is secured to the panel 3. This member has its side edges bent rearwardly and then laterally as indicated in Figure 2 and is secured to the panel as at 16. The door 10 when moved into open position is adapted to slide beneath the member 15. This member 15 is made of a single sheet of material and has a reinforcing rib 17 formed therein and beneath which the rib 11 on the door 10 will slide. The rods 13 extend upwardly within the member 15 and their upper ends are attached to the panel 3 exactly in the same manner that the lower ends thereof are attached to the panel. It will be noted in Figure 4 that the rods 13 are bowed slightly throughout their lengths. This is an important feature. Because they are so bowed, the rods 13 will always contact with the sides of the guides formed by the curled portions 12 on the door 10 with sufficient force to create sufficient friction to hold the door 10 in any position to which it is moved. Therefore, there is no danger of the door accidentally falling shut after it is once opened. As illustrated in Figure 4, when the door is closed, its upper end still extends beneath the portion 15. Therefore, there will be no danger of leakage. The door is protected at all times from the weather.

It will be readily apparent that the door may be easily adjusted vertically between its various positions. Because the ends of the rods 13 are loosely mounted so as to permit lateral movement, the door may be moved into its various positions with ease. However, because the rods 13 are slightly bowed, sufficient friction will be developed, as previously explained, to keep the door in any position into which it is moved.

In Figure 6, I illustrate means for securing the roof structure on top of the silo. This means comprises a plurality of brackets 18. The brackets are so shaped as to rest on the upper end of the silo. Each is provided with a hori-

zontal portion 19, a portion 20 which overlaps the inner surface of the silo wall and a downwardly extending portion 21 which overlaps the outer surface of the silo wall. This portion 21 has a hook 22 on its lower end which is adapted to cooperate with a ring 23 which extends around the upper portion of the silo wall. A ring of this type is usually employed on stave silos. The bracket 18 also has an inclined portion 24 at its upper end which is inclined to substantially the same extent as the roof panel 3. This portion 24 has a vertical slot 25 formed therein. A bolt 26 passes through the panel 3 and through the slot 25. It will be apparent that the brackets 18 serve as simple means for effectively holding the roof structure in place on the silo. The slot 25 and bolt 26 provide an adjustable connection which also aids in permitting the roof structure to be applied to a silo which is out of round or of an odd diameter. Thus, the bolt and slot connection 25—26 and the bolt and slot connection 6—7 cooperate with each other to permit the roof structure to be applied to a silo wall which is out of round or of an odd diameter.

I provide a small swinging door 27 in the upper portion 2 of the roof for permitting filling of the upper portion of the silo. This door is disposed towards the center of the silo so as to insure that the center portion thereof will be filled. 30

It will be apparent from the above that I have provided a silo roof having many desirable characteristics. This silo roof is made up of a plurality of panels of metal which are so formed that the roof is self-supporting. The joints 8 35 and the ribs 4 serve adequately to reinforce the panels to make them self-supporting. Furthermore, the adjustable joint 8 permits relative movement of the panels for the purposes previously explained. The joints 8 are of simple construction and may be readily formed. Furthermore, the means provided at these joints for securing the adjacent panels together is very simple. Also, the means provided for securing the entire roof structure to the silo is very simple 45 and efficient and permits application of the roof structure to a silo which is out of round. The door structure which I have provided in the side of the silo roof is of very simple construction and is safe to operate.

Various other advantages will be apparent from the preceding description, the drawing, and the following claims.

Having thus described my invention, what I claim is:

1. A silo roof comprising a plurality of panels arranged edge to edge, said panels being so formed that they gradually decrease in width from their lower edge to their upper edge and being arranged to form a frusto-conical structure, the adjacent edges of said panels having interfitting ribs, said ribs being of substantially semicircular cross-section and being disposed in superimposed relationship, said ribs gradually decreasing in width from their lower end to their upper end in accordance with the decrease in width of the panels, pin and transverse slot connections for securing the interfitting ribs together in such a manner as to permit relative movement therebetween, said interfitting ribs of the panels being the only supporting means provided at the joints between the panels, each of said panels having a rib intermediate the side edges thereof for reinforcing, said rib being of arcuate cross-section and gradually decreasing 75

in width from its lower end to the upper end in accordance with the decrease in width of the panel.

- 5 2. A silo roof comprising a plurality of panels arranged edge to edge, said panels being so formed that they gradually decrease in width from their lower edge to their upper edge and being arranged to form a frusto-conical structure, the adjacent edges of said panels having interfitting ribs, said ribs being of substantially semi-circular cross section and being disposed in

superimposed relationship, said ribs gradually decreasing in width from their lower end to their upper end in accordance with the decrease in width of the panels, pin and transverse slot connections for securing the interfitting ribs together in such a manner as to permit relative movement therebetween, said interfitting ribs of the panels being the only supporting means provided at the joints between the panels.
